MEANS FOR AND METHOD OF COATING
WALL SURFACES

John B. Kritzer, Oak Park, Ill.

Application February 5, 1936, Serial No. 62,477

5 Claims. (Cl. 101—129)

This invention relates generally to means for and methods of marking walls, and more particularly to patterns and methods for producing artificial stone or brick effects upon wall surfaces.

5 Methods for marking wall surfaces as, for example, the surfaces of stucco and plaster walls which have heretofore been suggested and with which I am familiar present numerous difficulties and disadvantages. One of the distinct disadvantages of these prior methods has been the use of relatively large, cumbersome and expensive patterns. It is, therefore, one of the important objects of the present invention to provide inexpensive, light-weight patterns whereby an improved method of marking wall surfaces may be practiced.

More specifically my invention contemplates the use of patterns which are of such weight that they will adhere without additional support to the soft surface of cement, plaster and the like, and thereby enable the user to very expeditiously apply a color to the wall surface not covered by the pattern.

Still another object of the present invention is 25 to provide a pattern which is not only of extremely light-weight, but which may be readily cut to fit any irregularity in the margin of the walls upon which the patterns are used as, for example, the wall areas surrounding doors, windows, beneath eaves, roof edges, etc. To this end my invention contemplates the provision of patterns constructed of thin, light-weight material such as cardboard or other similar flexible material which may be cut to any desired shape so as to 30 conform with the requirements at the place of application.

It is another object of the present invention to provide a pattern which is not only light in weight, inexpensive and easy to cut into various 40 shapes, but also sufficiently flexible so as to be self-conformable to irregularities in the surface contour of the plastic wall to which the pattern is applied in use. Most wall surfaces on the interior and exterior of buildings, for example, are not 45 perfectly flat and my invention contemplates a pattern which, when placed upon a surface having these irregularities, is sufficiently flexible to accommodate such irregularities.

The foregoing and numerous other objects and 50 advantages will be more apparent from the following detailed description when considered in connection with the accompanying drawing, wherein:

Figure 1 is an elevational view of a dwelling 55 having the exterior stucco or plastic surface

thereof marked in accordance with the teachings of the present invention;

Figure 2 is an enlarged perspective view of one form of pattern which may be used in applying the exterior design to the wall of the dwelling 5 shown in Figure 1;

Figure 3 discloses the manner in which the pattern of Figure 2 may be severed by the use of a pair of shears or other suitable cutting instrument to accommodate irregularities in the 10 margins of the wall as, for example, the angular disposition of the eaves shown in the upper central portion of the roof structure in Figure 1;

Figure 4 discloses a fragmentary portion of the pattern of Figure 2 applied to a fragmentary 15 portion of a cement or plaster wall such as the stucco wall of the dwelling of Figure 1, said application being made while the wall surface is still soft or impressionable;

Figure 5 is a fragmentary enlarged sectional 20 view of the wall and pattern taken substantially along the line 5—5 of Figure 4;

Figure 6 discloses the wall and pattern of Figure 4 after a coating of desired color has been 25 applied thereto;

Figure 7 is a fragmentary sectional view similar to Figure 5 taken substantially along the line 7—7 of Figure 6;

Figure 8 discloses the appearance of the wall structure of Figures 6 and 7 after the pattern 30 has been removed, and

Figure 9 is an enlarged fragmentary sectional view taken substantially along the line 9—9 of Figure 9, the detached pattern structure being 35 shown in its removed position.

Referring now to the drawing more in detail wherein like numerals have been employed to designate similar parts throughout the various figures, it will be seen that my invention contemplates the use of a panel or pattern, one embodiment of which is designated generally by the numeral 10 in Figure 2. Obviously my invention is in no sense limited to the particular design or pattern shown in the drawing, but contemplates any exterior or interior wall design or pattern 40 which the environment may require. This pattern or panel 10 is preferably made of very light flexible sheet material as, for example, pressed paper, cardboard or other suitable thin, light-weight, flexible material. I prefer to have the 45 surfaces of the pattern 10 coated or impregnated with a suitable waxy or paraffine substance which serves to materially reduce the affinity of the pattern or stencil surface for such substances as cement, plaster and the like.

In practicing my improved method by the use of the pattern 10, the surface of the dwelling or other structure is first provided with a coating 12 of any suitable cement or plaster material. 5 Obviously for exterior use cement or stucco is commonly employed, whereas for interior surfaces a plaster material may be preferable. Before the coating 12 has completely set and while it is still in a plastic or impressionable state the 10 pattern or stencil 10 is lightly pressed against the exterior surface of the coating 12. The affinity of the impressionable wall surface for the pattern 10 is sufficient to sustain the weight of the pattern without the use of any additional 15 support. In other words, the panel 10 is sufficiently light in weight so as to enable the normal adhesiveness or stickiness of the coating 12 to hold the pattern in position once it has been applied thereto.

20 Following the application of the panel to the wall surface, as shown in Figures 4 and 5, a second coating 14 of any selected color is applied to the exterior of the panel and the exterior of the coating 12 as clearly shown in Figures 6 and 7. 25 The panel or stencil 10 is then removed, as shown in Figures 8 and 9, so as to present a pattern on the wall surface conforming with the pattern 10. Thus the color of the pattern is similar to the color of the exterior of the coating 12, 30 the color of the remaining portion of the wall depending upon the color of the coating 14.

Attention is directed to the fact that the stencil 10 is not only of light weight, but is sufficiently flexible so as to enable it to be self-conformable 35 to any variations in the contour of the coating 12. Most wall surfaces, whether interior or exterior, have a certain amount of surface irregularity and thus if the panel or stencil 10 were constructed of metal or other similar stiff material, it would not only be too heavy, but would not be self-conformable to these surface variations or irregularities. It is, therefore, of the 40 utmost importance to form the panel 10 of light, flexible material.

45 In Figure 3 I have shown the manner in which the panel 10 may be cut into any desired shape to meet the needs incident to the use thereof. It will be apparent that when a pattern or design is to be provided along the margin of a sloping 50 eave, the pattern must conform with the eave slope. This can be accomplished very readily by the use of the pattern or panel contemplated by the present invention, it being only necessary to employ a pair of shears or suitable knife to cut 55 away a portion of the pattern to fit the particular wall margin. Likewise, in fitting the pattern around the windows or doors, said pattern may be suitably cut to the required shape. The stencils are so inexpensive that they need not be used 60 a second time, but can be cut to fit a particular portion of the wall margin and then thrown away. This type of stencil and method of marking should be compared with the relatively expensive methods which employ steel patterns and the like 65 which are very cumbersome to handle, are not self-conformable to the wall surface and cannot be shaped to fit odd sizes and marginal contours. In the use of these heavy steel patterns, one must employ a specially shaped pattern for each 70 unusually shaped wall area as compared with the present invention which contemplates a stencil or panel which is so inexpensive and easy to be cut that any marginal irregularity of a wall surface may be accommodated with no loss of time 75 and without any additional expense.

The invention is in no sense limited for use on the exterior of buildings, nor is it limited to any particular pattern or design. A light-weight, flexible pattern of any desired design may be employed for any wall surface which is sufficiently impressionable to receive the stencil. The impregnation or coating of the waxy substance upon the exterior of the stencil enables it to be removed without carrying with it any of the cement or plaster coating, and thereby enables a 10 design having clear and distinct lines of demarcation to be produced.

Having thus described my invention, what I claim as new and desire to secure by Letters Patent is:

1. The method of marking a wall surface which consists in embedding in a coating of impressionable material a panel of thin, light-weight, flexible stock forming a pattern, then applying a coating to the portion of the impressionable 20 coating not covered by the panel, and then removing the panel from said impressionable coating so as to present a design having clear lines of demarcation.

2. The method of marking a wall surface which 25 consists in partially embedding in a coating of impressionable material a panel of thin, light-weight, flexible stock forming a pattern, retaining said panel in position by the adhesiveness of the impressionable material, then applying a 30 coating to the portion of the impressionable coating not covered by the panel, and then removing the panel from said impressionable coating so as to produce a wall surface having slightly recessed uncoated portions outlining coated portions conforming to the panel pattern.

3. The method of marking a wall surface which 35 consists in slightly embedding in a coating of impressionable material a panel of thin, light-weight, flexible stock forming a pattern and having a waxy surface, then applying a coating to the portion of the impressionable coating not covered by the panel, and then removing the panel from said impressionable coating so as to 40 present a design having clear lines of demarcation.

4. The method of marking an impressionable 45 wall surface having a predetermined marginal shape, which consists in selecting a relatively thin, light-weight, flexible panel having the required design, cutting said panel to conform with the predetermined marginal shape of the wall surface, partially embedding said panel in the impressionable surface, applying a coating of 50 selected color to the area of said impressionable surface not covered by the panel, and then removing the panel so as to produce a wall surface having slightly recessed uncolored portions outlining colored portions conforming to the panel 55 design.

5. The method of marking an impressionable 60 wall surface which consists in embedding in said impressionable surface a relatively thin, light-weight, flexible panel of selected design, applying a coating of selected color to the wall area not covered by the panel, removing said panel so as to present a design having sharp lines of demarcation, and repeating the above mentioned 65 steps in connection with the remaining area of the wall surface until said entire surface has been provided with the design embodied in the applied panels.
